Filed Jan. 9, 1959, Ser. No. 54,097

Term of patent 14 years

(Cl. D71—1)

Fig. 1 is a side elevational view of a boat embodying our new design, the other side being substantially the same;

Fig. 2 is a rear elevational view thereof with the portion shown in broken lines Fig. 1 omitted for convenience of illustration only;

Figs. 3 and 4 are top plan and perspective views, respectively, of the portion shown in full lines in Fig. 1.

The dominant feature of our design resides in the stern portion shown in full lines.

We claim:

The ornamental design for a boat, as shown and described.
